UNITED STATES PATENT OFFICE.

JOSEPH E. BLOOMBERG, OF MILWAUKEE, WISCONSIN, ASSIGNOR TO THE WALLACE & SMITH CO., OF MILWAUKEE, WISCONSIN, A CORPORATION OF WISCONSIN.

WHIP.

1,157,838.

Specification of Letters Patent. Patented Oct. 26, 1915.

Application filed May 7, 1915. Serial No. 26,481.

To all whom it may concern:

Be it known that I, JOSEPH E. BLOOMBERG, a citizen of the United States, and resident of Milwaukee, in the county of Milwaukee and State of Wisconsin, have invented new and useful Improvements in Whips, of which the following is a description, reference being had to the accompanying drawings, which are a part of this specification.

The invention relates to whips and more particularly to that class of whips known as drovers' whips.

In whips of this type it is desired to have the lash swing freely in all directions and to accomplish this purpose, this invention designs to provide means hereinafter described for rotatably securing the lash to the stock of the whip so that the stock may be firmly grasped by the hand without interfering with the free swinging of the lash.

A further object of the invention is to rotatably secure the lash to the stock to permit the free movement of the lash while the stock is held tightly without wearing away the lash through direct engagement with the stock.

A further object of the invention is to provide a new and improved form of drover's whip.

The invention consists in the several features hereinafter set forth and more particularly defined by claims at the conclusion hereof.

In the drawings, Figure 1 is a vertical sectional view through the stock of the whip and portion of the lash embodying the invention; Fig. 2 is an elevational view of the whip embodying the invention.

The whip consists essentially of a lash, a stock and means for rotatably securing the lash to the stock to prevent wearing away of the lash through direct engagement with the stock. A band overlaps the end of the stock and the lash, thereby concealing the end of the stock and the end of the lash where the plaiting commences.

The stock consists of a rod 3 preferably of metal, having a conical end 4, a shoulder 5 adjacent said end, a curved annular bearing portion 6 adjacent said shoulder and a handle portion 7. The handle portion 7 is surrounded by filling 8 of any suitable material sufficient in thickness to give the stock

the desired diameter and an outer covering 9, preferably of leather, sewed together at the adjoining edges, as shown in Fig. 2, incases the filling 8. The end 10 of the filling and casing 9 converges toward the rod and terminates below the bearing portion 6 of the rod as shown in Fig. 1. The butt end 11 of the stock is provided with a knob 12, preferably formed of plaited leather strips.

The lash 13 of the whip comprises a filling 14, preferably of shot, extending down over the end 4 of the rod, a covering 15 for incasing the shot and secured therearound by a suitable winding 16, another covering 17 surrounding the covering 15 and secured therearound by a winding 18 and an outer plaited covering 19.

The means for rotatably securing the lash to the stock comprises a ring 20 seated in the bearing 6 of the rod 3 adjacent the shoulder 5 and extending slightly beyond the juncture of the shoulder 5 with the conical end 4, as shown in Fig. 1, and means for securing the ring to the lash.

The means for securing the ring 20 to the lash consists of means for binding the lower end of the lash to the ring. The lower end 21 of the covering 15 extends down over the ring 20 and is rotatably bound around the rod 3 between the ring 20 and the end 10 of the filling and covering on the handle by a suitable binding, such as a winding 22. Thus the bearing 6, shoulder 5 and the covering 15 form a pocket for the ring and the ring is held to the lash by the covering 15. The lower end 23 of the covering 17 extends down over the end 21 to a position adjacent the end 10 of the handle and is bound around said end 23 by the winding 18. A band 24, preferably of plaiting, overlaps the lower end 25 of the covering 19 and the upper end of the stock thereby concealing and protecting the end of the stock, the rotatable securing means and the end 25 of the lash. With this construction, the ring 20 contacting with the rod 3 takes the wear off the covering 15 of the lash to which it is securely connected and the shot filling 14 surrounding the end 4 of the rod 3 down to the ring 20 forms a bearing in which the rod 100 is free to turn within the lash which cooperates with the ring 20 secured to the lower end of the lash to permit rotary move-

105

ment of the lash in all directions with respect to the stock.

The invention thus exemplifies a drover's whip in which the lash is firmly secured to the stock though it may rotate with respect thereto without injury to the stock or that portion of the lash which is secured to the stock.

The invention is not to be restricted to the details of construction herein set forth, but may be varied so as to be within the scope of the appended claims.

What I claim as my invention is:

1. In a drover's whip, the combination with a lash, of a stock comprising a rod having an enlarged upper end disposed within the butt end of the lash, rotatable means surrounding the rod beneath said enlarged end, and means for securing said lash to said rotatable means and to said rod below said rotatable means to permit rotary movement of the lash with respect to the stock.

2. In a drover's whip, the combination, with a lash having a shot filling, of a stock comprising a rod having its upper end bearing in said filling and a shouldered portion near said end, a member rotatably mounted on said rod beneath said shouldered portion and contacting therewith, and means for securing the lash to said rotatable member to permit rotary movement of the lash with respect to the stock.

3. In a drover's whip, the combination, with a lash having a shot filling, of a stock comprising a metal rod having its upper end bearing in said filling and a shouldered portion near said end, a ring mounted on said rod beneath said shouldered portion and contacting therewith, and means for securing the lash to said ring to permit rotary movement of the lash with respect to the stock.

4. In a drover's whip, the combination, with a lash having a metal filling, of a stock comprising a metal rod having its upper end bearing in said filling, said rod having a shouldered portion near said end and an annular bearing adjacent said shouldered portion, a ring rotatably mounted in said annular bearing contacting with said shouldered portion and extending therebeyond, and means for securing said lash to said ring

to permit rotary movement of the lash with respect to the stock.

5. In a drover's whip, the combination, with a lash, of a stock comprising a metal rod having a handle portion and an enlarged conical upper end extending into the lash and forming a shoulder with the handle portion of the rod and having an annular bearing adjacent said shoulder, rotatable means mounted within said lash and on said bearing beneath said enlarged end, and a portion of the lash surrounding said means and secured to said rod to permit rotary movement of said means and lash with respect to the stock.

6. In a drover's whip, the combination, with a lash having a metal filling, of a stock comprising a metal rod having its upper end bearing in said filling, said rod having a shouldered portion near said end and an annular bearing adjacent said shouldered portion, a ring mounted in said annular bearing contacting with said shouldered portion and extending therebeyond, and a portion of the lash surrounding said ring and secured to said rod beneath the ring to permit rotary movement of the said ring and lash with respect to the stock.

7. In a drover's whip, the combination, with a lash, of a stock comprising a rod having an enlarged upper end disposed within the butt end of the lash, rotatable means carried by the lash and surrounding the rod beneath said enlarged end, and binding means for fixedly securing said lash to said rotatable means and directly but movably to said rod to permit rotary movement of the lash and stock with respect to each other.

8. In a drover's whip, the combination, with a lash having a shot filling, of a stock comprising a rod having its upper end bearing in said filling and a shouldered portion near said end, a member rotatably mounted on said rod beneath said shouldered portion and contacting therewith, and means for binding the lash to the rod for rotary movement, said rotatable member being secured between said shouldered portion and the bound end of the lash.

In testimony whereof, I affix my signature.

JOSEPH E. BLOOMBERG.
